UNITED STATES PATENT OFFICE.

JULIAN O. ELLINGER, OF NEW YORK, N. Y.

COLLAPSIBLE METALLIC STRUCTURE.

1,140,448.

Specification of Letters Patent. Patented May 25, 1915.

Application filed October 15, 1912. Serial No. 725,795.

To all whom it may concern:

Be it known that I, JULIAN O. ELLINGER, a citizen of the United States, and a resident of the borough of Manhattan, city and State of New York, have invented certain new and useful Improvements in Collapsible Metallic Structures, of which the following is a specification.

This invention relates to skeleton structures fabricated of metallic members adapted to be used as columns or beams in concrete reinforcements and consists of the novel features hereinafter set forth and illustrated in the accompanying drawing.

One of the objects of the invention is to provide such a structure composed of a series of longitudinal members arranged in angular relation to each other and having members pivotally connecting the same in such manner that the structure may be collapsed and stored or transported and may be readily opened out to its expanded condition for use.

Other objects will appear from the hereinafter description.

One specific form of the invention is illustrated in the accompanying drawing.

Referring to the drawing in which the same reference character indicates the same part in the several views: Figure 1 is a side elevation of the structure in its expanded form. Fig. 2 is a cross section of the same on line 2 of Fig. 1. Fig. 3 is a perspective view of one of the pivoted cross members. Fig. 4 is a cross sectional view of the structure in its collapsed form.

In the illustration the structure is square in cross section although it may be of other suitable polygonal shape. The parts marked 10, 11, 12 and 13 on the drawing represent longitudinal members arranged at the corners of the angles of a square or rectangle when expanded. The longitudinal members 10 and 12 are connected together by a series of cross members 14 which are spaced apart and provided with welding projections 14^a, by which the ends thereof are rigidly secured to said longitudinal members 10 and 12, preferably by electric welding. The opposite longitudinal members 11 and 13 are also connected together by a series of cross members 15, spaced apart and provided with welding projections 15^a. 16 is another series of cross members, one end 16^a of which is formed into an eye which surrounds the longitudinal member 10, and extends over one

end of the cross member 14. The other end 16^b is similarly formed into an eye which surrounds the longitudinal member 11 and one end of the cross member 15. 17 is another series of pivoted cross members the ends, 17^a and 17^b, of which respectively are turned around the longitudinal members 12 and 13 and span the respective ends of the cross members 14 and 15 adjacent to the longitudinal members 12 and 13. There may also be provided additional longitudinal members 20 and 21 which are rigidly secured to the respective cross members 14 and 15 about midway of the latter. This construction may also be provided with additional longitudinal members 18 and 19. When said members are provided the pivoted cross members 16 and 17 intermediate the ends thereof may be turned into eyes 16^c and 17^c which loosely surround and form pivotal connections with the longitudinal members 18 and 19. The construction is such that when the diagonally opposite corner members 10 and 13 or 11 and 12 are brought toward each other the structure is collapsed to the form shown in Fig. 4, for storage or shipping and when the said longitudinal members are moved from each other they are expanded for use to the position shown in Figs. 1 and 2.

While, as stated, the different rigid elements are connected together by electric welding and certain of the parts are provided with ridges for this purpose, yet it is to be understood that the said elements may be connected together by other than electric welding and in some cases the welding ridges may be dispensed with.

Having now described my invention what I claim as new and desire to secure by Letters Patent is:

1. In a device of the class described, a series of parallel longitudinal members, a series of cross members spaced apart and having their ends rigidly connected to a pair of said longitudinal members, another series of cross members spaced apart located opposite the first mentioned cross members and having their ends rigidly connected to a second pair of longitudinal members, a third series of cross members spaced apart having each end turned around the adjacent longitudinal members of each pair and also around the adjacent ends of the respective rigid members, a fourth series of cross members opposite the last mentioned cross

- members, also having their ends respectively turned around the opposite pair of longitudinal members, the ends of the two last mentioned series of cross members forming pivotal connection with the longitudinal members.
2. In a device of the class described; a series of parallel longitudinal members, a series of cross members spaced apart and having their ends rigidly connected to a pair of said longitudinal members, another series of cross members spaced apart located opposite the first mentioned cross members and having their ends rigidly connected to a second pair of longitudinal members, a third series of cross members spaced apart having each end turned around the adjacent longitudinal members of each pair and also around the adjacent ends of the respective rigid members to form pivotal connections, a fourth series of cross members opposite the last mentioned cross members, also having their ends turned around the opposite longitudinal members to form pivotal connections, a longitudinal member between the first pair of longitudinal members rigidly connected to the first mentioned cross members, another longitudinal member located between the second pair of longitudinal members and rigidly connected to the second mentioned series of cross members, and longitudinal members intermediate the ends of the respective series of pivoted cross members, each of said cross members being provided with eyes intermediate the ends thereof to loosely receive the last mentioned longitudinal members.
3. In a collapsible metallic reinforcement for concrete, side frames comprising longitudinal and transverse members rigidly united together and independent members

pivots connecting said side frames to each other, whereby one pair of the diagonally opposed longitudinal members will collapse toward each other.

45

4. In a collapsible metallic reinforcement for concrete columns, the combination of spaced apart parallel longitudinal bars arranged in pairs, transverse members attached to the bars of each pair to form separate frames and members pivotally connecting said frames together whereby two of the diagonally opposed longitudinal bars will collapse toward each other.

50

5. In a collapsible metallic reinforcement for concrete, the combination of spaced apart longitudinal members arranged in pairs, transverse members welded to the members of each pair to form separate rigid frames and straps pivotally connecting said frames together whereby the structure will collapse by one longitudinal member of each pair approaching one longitudinal member of the other pair and the other longitudinal members will move away from each other.

65

6. In a collapsible metallic reinforcement for concrete columns, side frames comprising longitudinal and transverse bars secured together and independent members pivotally connecting said side frames whereby said side frames will collapse toward each other without increasing the length of the structure when collapsed.

70

In witness whereof I have hereunto set my hand at the borough of Manhattan, city and State of New York, this 18th day of June, 1912.

JULIAN O. ELLINGER.
